Wesley L. Barr

ATTORNEY

UNITED STATES PATENT OFFICE

ALBERT CALLSEN, OF NUEREMBERG, GERMANY, ASSIGNOR TO WESTINGHOUSE ELECTRIC
& MANUFACTURING COMPANY, A CORPORATION OF PENNSYLVANIA

INDUCTION METER

Application filed August 30, 1928, Serial No. 303,013, and in Germany August 4, 1927.

My invention relates to induction meters and more particularly to means for improving the operation of induction meters upon changes of temperature.

5 My invention has for an object to provide means for compensating induction watthour meters for errors incident to temperature changes.

In my British Patent No. 277,015 dated 10 May 24, 1928, I describe and claim means for compensating an induction watthour meter for temperature errors including a thermal alloy having a high negative temperature coefficient of permeability disposed in one of 15 the driving flux paths.

Figs. 1 and 2 of the above-mentioned patent illustrate how the thermal alloy members may be mounted on the voltage magnet so that they are in the path of the current driving 20 flux.

25 My invention provides means for simply and efficiently accomplishing the same result with a small amount of material by mounting the thermal alloy directly on the voltage magnet by means of screws. The thermal alloy members are each angular in form so that one limb may be secured to the voltage magnet and the other limb extend into the air gap, containing the armature disc, in the path of 30 the flux from the current magnet.

This arrangement is diagrammatically illustrated in the drawing affixed hereto and forming part of my specification.

The drawing shows a perspective view of 35 the two driving magnets located at an enlarged distance apart for the purpose of disclosing the lower portions of the voltage magnet.

The voltage magnet S, with the potential 40 winding s, consists of a U-shaped core provided with limbs S₁ and S₂ having a yoke S₃ and a central member S₄ upon which the potential coil s is mounted. The two core limbs of the voltage magnet are held together by 45 means of a brass bar m, which is attached to the core limbs S₁ and S₂ by screws a₁ and a₂, respectively, and to the central member S₄ by a screw a₃. The upper end of the member S₄ fits into a recess of the yoke S₃ that is cov- 50 ered by plates b₁ and b₂.

A contact clip R is also secured to the voltage magnet S by the screws a₁ and a₂, and a tongue v on said clip passes around the edge of the armature disc A and constitutes, together with the slightly projecting pole of 55 the core S₄, an air gap L for the potential driving flux.

A main current magnet H, provided with a winding h, is so disposed, in the assembled driving system, that the pole portions 60 thereof are adjacent to the potential magnet, as indicated in broken lines at H₁ and H₂.

Thermal alloy elements W₁ and W₂, having a negative temperature coefficient of permeability, are preferably angular having one 65 limb thereof secured to the voltage magnet by means of the screws a₁ and a₂, and the free limb thereof located in the air gap, as shown.

The thermal alloy angles W₁ and W₂ may be readily mounted on the shunt pole portions of standard existing watthour meters without altering their structure, thereby providing ready means for immediately improving the operation of present meters without the necessity of redesigning them. 70 75

Various changes and modifications may be made without departing from the spirit of my invention and the appended claims and I desire therefore, that only such restrictions be placed upon them as are imposed by the prior art. 80

I claim as my invention:

1. The combination with an induction meter including relatively movable magnetic-flux co-acting members disposed in slightly-spaced substantially parallel surface-to-surface relation to provide a narrow air gap therebetween, of a temperature-compensating element embodying a magnetic portion in said gap, and supporting means therefor exterior to the gap. 85 90

2. The combination with an induction meter including a disk armature, and means for actuating the armature including a magnet element having a pole-end surface in 95 slightly-spaced substantially parallel surface-to-surface relation to the armature to therewith provide a narrow air gap, of temperature-compensating means embodying a magnetic portion in said gap, and support- 109

ing means therefor mounted on said magnet element exterior to the gap.

3. The combination with an induction meter including a disk armature, and means for actuating the armature including a magnet element having a pole-end surface in slightly-spaced substantially parallel surface-to-surface relation to the armature to therewith provide a narrow air gap, of temperature-compensating means embodying a magnetic member having angularly related portions, one of which is disposed in said gap and one of which is removably mounted on said magnet element exterior to the gap.

15 In testimony whereof, I have hereunto subscribed my name this 17th day of July, 1928.

ALBERT CALLSEN.
